UNITED STATES PATENT OFFICE.

ALLEN LOOMIS, OF DETROIT, MICHIGAN, ASSIGNOR TO PACKARD MOTOR CAR COMPANY, OF DETROIT, MICHIGAN, A CORPORATION OF MICHIGAN.

HYDROCARBON-MOTOR.

1,122,138.

Specification of Letters Patent. Patented Dec. 22, 1914.

Application filed March 26, 1912. Serial No. 686,366.

To all whom it may concern:

Be it known that I, ALLEN LOOMIS, a citizen of the United States, residing at Detroit, county of Wayne, State of Michigan, have 5 invented certain new and useful Improvements in Hydrocarbon-Motors, of which the following is a specification.

This invention relates to hydrocarbon motors, and more particularly to the ignition 10 systems thereof.

In the use of hydrocarbon motors for motor vehicles and motor boats it is customary to provide both battery and magneto for the ignition, the high tension current being carried from the distributor to the respective 15 spark plugs by well insulated wires, and in some cases switches are used at the plugs for the purpose of conveniently cutting out one or several of the cylinders in making 20 tests on the motor. It has been found that when the motor is running with any of these switches open, there being no outlet for the high tension current, the voltage tends to build up to such an extent that there is 25 danger of breaking down the insulation in the transformer coils or other parts of the high tension circuit. In arranging the ignition circuits one side of each circuit is usually "grounded" on the motor frame and 30 cylinders, and in the present invention, in order to avoid the danger of breaking down the insulation when any of the switches are open, I have provided means for grounding the switches on the motor cylinder when 35 they are moved from contact with their respective spark plugs. In combination with the means for grounding the switches I have provided a neat and substantial housing 40 for the ignition wires and support for the switches and contact or grounding devices.

Other objects and the features of novelty of the invention will be apparent from the following description taken in connection 45 with the accompanying drawings.

In the drawings, Figure 1 is a side elevation of a hydrocarbon motor embodying my invention; Fig. 2 is an end elevation of a portion of the motor shown in Fig. 1; Fig. 50 3 is a side elevation of the backing member of the ignition circuit conduit; Fig. 4 is a back view of the facing member of the ignition circuit conduit; Fig. 5 is a wiring diagram for the ignition system.

55 Referring to the drawings, 10 indicates a

section of the motor crank case upon which are mounted the cylinders 11, these cylinders being preferably cast in pairs, as shown in Fig. 1. The motor, which is preferably of the watercooled type, is provided with a 60 discharge water conduit 12, which is arranged centrally above the cylinders and communicates with the jackets thereof by means of suitable branches 13, one of which is clearly shown at the right side of Fig. 1. 65 The inlet and exhaust ports for the motor are preferably arranged on one side thereof and communicate with the interior of the cylinder by means of passages arranged at the top of the cylinders and into which 70 spark plugs 13 project. Bosses or lugs 14 are arranged on the side of the water conduit 12 toward the spark plugs and an ignition circuit conduit comprising the backing member 15 and the facing member or wiring board 16, are arranged on these bosses or lugs. Suitable switches 17 are mounted on the front side of the facing member 16 in line with the spark plugs of each pair of cylinders, as clearly shown in Fig. 1. These 75 switches are preferably arranged to have universal movement and are secured to the facing member by means of suitable screws 18 which engage nuts 19 embedded in the rectangular recesses 20 in the rear side of 80 the facing member 16. In order to prevent the switches from turning on the screws 18, suitable dowel pins 21 are provided. The backing member 15 of the ignition circuit conduit is preferably made of wood or other 85 insulating material and of U-shaped cross section and provided with upward extensions 22, through which the bolts 23 are passed. As will be seen from Fig. 2, the front side of the backing member 15 is hollowed out and receives the facing member 90 16, in the rear side of which are formed 95 suitable grooves for the ignition circuits.

As shown in Fig. 1, the magneto 24 is arranged at one side of the motor and driven 100 by means of a shaft 25. The magneto is provided with the usual distributor 26 for distributing the ignition current to the various cylinders in proper sequence and the various conductors which connect with the 105 magneto and the distributor pass upwardly through the insulating tube 27 and through suitable openings 28 in the facing member 16, these openings communicating with the grooves in the back of said member.

In order to secure the ignition circuit conduit against the bosses 14 and also provide means for short-circuiting the circuits when the switches are not connected with the spark plugs, clips or brackets 29 are provided. These clips or brackets are provided with a downwardly extending portion 30 which engages the face of the ignition circuit conduit and is secured thereto by means of a suitable screw 31 which extends through the facing member 16 and engages a nut mounted in the rear of the latter in a manner similar to the arrangement of the nut 19 above described. The clip or bracket 29 is also provided at the top with a lateral extension 32, which overlies the extension 22 on the backing member 15 and has its end in engagement with the lug 14. The bolt 23 passes through the lug 14, the extension 22 and the clip 29, and is provided on the front side of the latter with a nut 33, by means of which the extension 32 on the bracket is drawn against the lug 14 and the lower portion 30 of the bracket clamped against the face of the ignition circuit conduit so as to hold the latter against the boss or lug 14. The brackets 29 are also provided with extensions 34 along the face of the ignition circuit conduit and the ends of these extensions are turned outwardly and downwardly in substantial alinement with the spark plugs 13 and the switches 17, as clearly indicated in Figs. 1 and 2. These outwardly and downwardly extending arms 35 are spaced a sufficient distance from the top of the spark plugs to permit the switches to assume a position where they are not in contact with either the spark plugs or the arms. On account of the arms 35 being arranged directly above the spark plugs, it will be seen that the switches may be quickly thrown from contact with the spark plugs to the arms by an upward movement. By providing a universal movement for the switches any disalinement of the arms and spark plugs will not interfere with the operation of the switches.

Referring to Fig. 5, in which the wiring diagram for the ignition system is shown, 50 indicates the storage battery for supplying the ignition current when the magneto is not in use. The currents generated by the magneto and by the battery are brought to the usual switch 37 by means of which either the battery or the magneto may be thrown into service. From the switch 37 the current is passed through the usual induction coil and from the latter the high tension current is carried by means of the wire 38 to the distributor 39, by which it is distributed to the cylinders of the motor through the circuits 40, one of which is shown complete. The wires 40 are brought through the insulating tube 27 and the openings 28 in the wiring board and arranged in the grooves 41, 42, 43, 44, 45 and 46, from which they pass through openings 47 to the front of the wiring board and connect with the various switches. When the switches are in contact with the spark plugs the current passes through the switch and across the gap of the spark plug and to the ground. When the switches are in contact with the arms 35, as shown in dotted lines in Fig. 2, the current will pass through the switches to these arms and from the latter through the lugs 14 to the ground. The low tension wires leading from the magneto to the switch and coil 37, which is usually located on the dash-board of the vehicle, are carried through the tube 27 and the groove 48 in the back of the wiring board.

It will be seen that the above-described arrangement of the ignition circuits provides for their complete insulation and produces a simple and neat appearance and the wires are so located that they are not liable to be injured in any way. By providing the clips or brackets 29, which carry the arms 35, I have produced a construction which is simple and effective in operation and serves the double purpose of securing the ignition circuit conduit in position and providing a means for grounding the ignition circuits, when they are not closed, through the spark plugs.

Having thus described my invention, what I claim is:

1. In a hydrocarbon motor, the combination with the cylinders thereof, of a conduit mounted thereon, a wire conduit, comprising a backing member, detachably arranged on said first conduit, and a facing member detachably secured to said backing member.
2. In a hydrocarbon motor, having a plurality of water jacketed cylinders, a conduit communicating with the cylinder jackets and having lugs arranged thereon, a wire conduit comprising a backing member and a detachable facing member, said wire conduit being supported on said lugs and removable therefrom as a unit, and means for detachably securing said members together.
3. In a hydrocarbon motor having a plurality of water-jacketed cylinders, a water conduit extending along the top of the cylinders and communicating with the jackets thereof, an ignition circuit conduit, extending alongside of said water conduit, spark plugs for said cylinders, switches carried by the ignition circuit conduit and arranged to contact with the spark plugs, brackets secured to the ignition circuit conduit and having extensions adapted to be engaged by said switches to short-circuit the ignition circuits, and means for securing said brackets to said water conduit and to clamp the ignition circuit conduit thereto.
4. In a multiple-cylinder hydrocarbon motor, an ignition circuit conduit comprising

ing a backing member and a facing member, one of said members having grooves for ignition circuits on the side adjoining the other of said members, switches on said facing member having connection with the ignition circuits, spark plugs, and members having electrical connection with the cylinders and arranged to be engaged by said switches, to short circuit the ignition current around the spark plugs.

5. In a multiple-cylinder hydrocarbon motor, an ignition circuit conduit supported above the cylinders and having grooves for the ignition circuits concealed therein, switches mounted on said conduit and connected with the ignition circuits, and a member having electrical connection with the cylinders and arranged to be engaged by a plurality of said switches for the purpose described.

6. In a multiple-cylinder hydrocarbon engine, an ignition circuit conduit supported above the cylinders and having grooves for the ignition circuits concealed therein and openings from said grooves to one of the faces of the conduit, switches mounted in pairs on said conduit adjacent said openings and connected with the ignition circuits, and members mounted on said conduit between each pair of switches and having projections or contact arms arranged to be engaged by the switches, for the purpose described.

7. In a multiple-cylinder vertical hydrocarbon engine, vertically arranged supports above the cylinders, an ignition circuit conduit of substantially oblong cross-section arranged on said supports with its longer axis vertical, switches mounted on the side of said conduit and connected with the ignition circuits, members arranged on the side of said conduit between the switches and provided with contact arms adapted to be engaged by the switches and having a portion thereof extending over the top of said conduit and bearing against said supports, and bolts arranged to clamp the upper portion of said members against said supports and the lower portion thereof against said conduit.

8. In a hydrocarbon motor provided with an electric ignition circuit and a spark plug, having one terminal thereof electrically connected with one side of said circuit, the combination of a support mounted on the

motor, a switch mounted on said support and electrically connected with the other side of said circuit and adapted to be moved into engagement with the other terminal of the spark plug, and an arm carried by said support and having electrical connection with the first-mentioned side of said circuit and adapted to be engaged by said switch when the latter is moved out of engagement with the spark plug.

9. In a hydrocarbon motor having a vertical cylinder, an electric ignition circuit and a spark plug having one terminal thereof electrically connected with the cylinder, the combination of a support mounted on the top of the cylinder and electrically connected with the latter, a switch for said circuit carried by said support and insulated therefrom and adapted to engage the other terminal of said spark plug, and an arm carried by said support and electrically connected therewith and adapted to be engaged by said switch when the latter is moved out of engagement with the spark plug.

10. In a hydrocarbon motor having a plurality of cylinders, electric ignition circuits and spark plugs, the combination of a plurality of switches in said circuits and each adapted to engage one of said spark plugs, and a member carried by said motor and having a plurality of arms, said arms being arranged to be engaged by said switches when the latter are moved out of engagement with said spark plugs.

11. In a multiple-cylinder vertical hydrocarbon motor having electric ignition circuits and spark plugs, the combination of a support mounted on the top of said cylinders, switches in said circuits, carried by said support and insulated therefrom and each adapted to engage one of said spark plugs, and a member carried by said support and electrically connected therewith and having arms arranged adjacent to said spark plugs, said arms being adapted to be engaged by said switches when the latter are moved out of engagement with the spark plugs.

In testimony whereof I affix my signature in presence of two witnesses.

ALLEN LOOMIS.
